ALBERT RUPRECHT, OF ASPERG, GERMANY.

IGNITION PLUG.

1,412,751.

Specification of Letters Patent. Patented Apr. 11, 1922.

Application filed September 18, 1912. Serial No. 720,954.

(GRANTED UNDER THE PROVISIONS OF THE ACT OF MARCH 3, 1921, 41 STAT. L., 1313.)

To all whom it may concern:

Be it known that I, ALBERT RUPRECHT, a citizen of the German Empire, residing at Asperg, in the Kingdom of Wurttemberg, 5 Empire of Germany, have invented certain new and useful Improvements in Ignition Plugs, of which the following is a specification.

In ignition plugs for internal combustion engines, it is usual to make the casing of the plug of iron or steel, i. e. the part which is screwed into the engine cylinder, and which also covers the insulating sleeve. A disadvantage in this type of plug is that the plug 10 casing is apt to become fixed or bound in the cylinder, due for example to rust, thus making the loosening or changing of the plug very difficult. In order to remove this disadvantage the whole plug casing has been 15 made of brass or a similar non-corrosive metal, which, however, has the disadvantage that in consequence of the higher co-efficient of expansion of brass compared with iron or steel the plug becomes loose.

20 The object of the present invention is to remove the above mentioned disadvantages of the known constructions and to unite the advantages of brass, or a similar metal, with those of iron. For that purpose the plug casing according to the invention, is made of 25 these two metals, the screw threaded nipple being of brass or other non-corrosive metal, thus preventing it being rusted in the cylinder, whereas the head formed as a nut is 30 made of iron or steel, so that loosening of the plug cannot occur. In order to get a firm 35 connection between these two parts of the plug casing composed of different metals, the screw threaded nipple is provided with several 40 saw cuts or slits in its upper edge and is then tightly screwed into the nut in which the insulator has been placed, whereby on the one hand the screwed nipple is expanded by 45 the shoulder of the insulator and is tightly connected with the nut, and on the other hand, the shoulder of the insulator is tightly 50 pressed against a washer inserted between the insulator and the shoulder of the nut, or head of the plug casing.

50 The accompanying drawing illustrates one form of the invention, Figure 1 being a

sectional elevation and Figures 2 and 3 being plans.

The nut *a*, or head of the plug casing, according to the invention, is made of iron or 55 steel, whereas the screwed nipple *b*, by which the plug is secured to the motor cylinder, is made of brass, or a similar metal. The screwed nipple *b*, is provided with several saw cuts or slits in its upper edge, in order to 60 make it more flexible. It is screwed into the nut or head *a*, after the usual insulator *c*, has been placed therein, a washer being placed between the insulator and nut. The shoulder on the insulator *c*, on the one hand slightly 65 expands the upper saw cut edge of the screwed nipple *b*, and presses it tightly in the thread of the nut *a*, and on the other hand, it compresses the washer *d*, tightly 70 between itself and a shoulder on the nut *a*. 70 As usual the electrode *e*, is passed through the insulator *c*, and is fastened by means of a nut *g*, a spring washer *f*, being provided. A nut *h*, secures the conductor.

I claim:

75 In an ignition plug, in combination, a casing comprising a head portion of iron and a nipple of non-corrosive metal, said head portion being provided with an inwardly extending shoulder at its upper end and having 80 its lower part externally threaded, said nipple being externally threaded and having its upper end engaging the threaded portion of said head portion, the upper end of said nipple being slotted, an electrode supporting 85 insulator supported by said casing, said insulator being provided with a shoulder adapted to engage the upper slotted end of said nipple whereby the upper portion of said nipple will be expanded and forced 90 into the threaded portion of said head portion, said insulator being provided with a second shoulder registering with the shoulder on said head portion, and a washer interposed between said last mentioned shoulder. 95

In testimony whereof I affix my signature in presence of two witnesses.

ALBERT RUPRECHT.
